SPLICING FOR RAFTER DRAINING MEMBERS

Filed Dec. 31, 1927

Inventor
Philip L. McKee,
By Cheever & Cox Atty's

UNITED STATES PATENT OFFICE

PHILIP L. MCKEE, OF CHICAGO, ILLINOIS

SPLICING FOR RAFTER DRAINING MEMBERS

Application filed December 31, 1927. Serial No. 243,807.

My invention relates to roof structures particularly for greenhouses, and the general object of my invention is to provide an improved splicing joint for roof bars, particularly for roof bars of greenhouses whereby a roof bar sufficiently long to extend from the ridge pole the entire width of the sloping roof may be provided by splicing together two or more shorter pieces of this 10 roof bar.

In the construction of greenhouses, the panels of glass are supported by roof bars which extend from the ridge pole in a downwardly inclined direction the entire width of 15 the greenhouse on each side of the ridge pole. These roof bars are constructed so as to carry the glass panels at their upper portions and are provided with drain grooves at their lower portions and preferably immediately 20 above their connections to the purlins upon which they are supported and to which they are fastened. These roof bars are necessarily very long to correspond with the width of the sloping roofs of the greenhouses and it is 25 not practicable, from a commercial standpoint, to provide continuous pieces of wood for these roof bars. Hence, it becomes necessary to splice or fasten together two or more shorter sections to form a continuous 30 roof bar which, of course, makes a cheaper construction. In the formation of these splices much difficulty has been experienced by the improper drainage of water of condensation which collects on the under surfaces 35 of the glass panels of the roofing. These spliced joints are generally located directly at the purlins and considerable difficulty has been experienced by these splicing joints due to the fact that the water of condensation coming from the under surface of 40 the glass panels and also the drain water running along the drain grooves of the roof bars, had a tendency to run along the lines of splice of the roof bars whereby to cause 45 dripping of this drain water into the greenhouse below or to cause it to flow improperly and flow and drip along the purlins and cause their rusting and unsightly appearance.

50 One of the objects of my present invention

is to provide a splicing for the roof bar wherein the lines of splice are constructed and arranged so as to drain the water down the drain guides of the roof bar and positively prevent the water of condensation and 55 drain water from following the lines of splice and from draining or dripping upon or across the purlins.

These and other objects of my invention will be apparent from a perusal of the following specification when taken in connection with the accompanying drawings, 60 wherein—

Fig. 1 is a view through a portion of a greenhouse roof showing the manner in 65 which one of the inclined roof bars is spliced together and connected to a purlin;

Fig. 2 is a perspective view of two pieces 70 of roof bar detached and somewhat spaced apart; and

Fig. 3 is a section on line 3—3 of Fig. 1. In the illustrated form of my invention, the roof structure shows one of the roof bars as extending in an upwardly inclined 75 direction as is well known in the art, and this roof bar in the present instance is formed of two sections 2 and 4 spliced together in accordance with my invention, and the spliced joint is rigidly and firmly 80 held in assembled position by means of a metal clamp 6 embracing the lower sides of the two sections 2 and 4 directly at the splice, and this clamping member 6 is provided with perforations through which pass 85 bolts 8 in turn passing through holes 10 in the sections 2 and 4 whereby the clamp 6 on the spliced sections 2 and 4, is securely bolted in position. In addition, the clamp 6 has another bolt 12 passing transversely 90 through its bottom and through the upper flange 14 of the metal purlin 16, the assembly being held in secure position by means of the nut 18. In this manner the assembled splice sections 2 and 4 of the roof bar are securely and firmly connected to and mounted upon the cross purlin 16. This provides a very firm and simple assembly. 95

The main feature of my present invention resides in the splicing arrangement of the 100

two sections 2 and 4 of the roof bar. As is well known in the art, the roof bar is provided on its opposed sides near its lower portions with draining grooves 20 and 22 along which the water of condensation or any leakage water will run downwardly to discharge at convenient points at the lower portion of the greenhouse. These drain grooves are most important since water of condensation collecting on the under surfaces of the glass panels 24, will collect at the upper portions of the roof bars and will run downwardly there-along into these drain grooves, and it is very important that the water in these drain grooves 20 and 22 and any water of condensation or leakage water, be directed wholly down the grooves and that it not be permitted to leak onto or across the purlins or other cross beams and thereby drip into the greenhouse and at the same time deface and rust the purlins.

In carrying out my improved splicing arrangement, I provide the lines of splice in such a manner as to take full advantage of the angle of inclination of the roof bar sections 2 and 4 together with the arrangement and location of the drain grooves 20 and 22 thereon; and also the manner in which the glass panels 24, or any sash members carrying these glass panels, are mounted upon the roof bar. For instance in referring to the drawings it will be seen that I provide a sort of Z-splice line wherein one of the outer legs of the splice, designated at 26, extends from a point 28 outwardly and this point 28 is that point at which the glass panel 24 seats on the flange 30 formed by a neck 32, and it will also be seen that the adjacent line of splice 34 extends from this point 28 to a second point 36 in a forward direction, that is, in the opposed direction relative to the first line of splice 26. In a similar manner a third line of splice 38 runs in a direction opposed to the line of splice 34 or somewhat parallel to the line of splice 26 and this line 38 terminates at the point 40 at the lower edge of section 4. The point 36 is located directly at the drain groove either 20 or 22, depending upon the side of the roof bar upon which it is located. Particular attention is directed to the fact that the roof bar sections 2 and 4, when assembled, are arranged in inclined position relative to the horizontal and this arrangement is particularly controlling with reference to the lines of splice 26, 34, and 38 and with reference to the drain grooves 20 and 22 and the angle of inclination of the panels 24 because, as thus arranged, when water condenses on the under side of the panel 24 as shown in Fig. 1, this water will creep along the under surface of the panel and not contact with the top portion of the roof bar and will flow downwardly by gravity until it strikes the splice line 34. It will then be

deflected by this splice line downwardly into one or the other of the drain guideways 20 or 22. If it attempt to flow along the splice line 26, it will be carried along the upper face of the panel 24. So also, when the water flowing on the outside of the panel 24 strikes the splice line 26, it will be directed forwardly and downwardly and will not flow backwardly or rearwardly because it will not flow uphill as the direction of inclination of the splice line 26, as seen in Fig. 1, is forwardly and downwardly and, therefore, the water cannot flow in the reverse direction in this line 26 because to do so would be to have the water flow uphill. In a like manner the water which flows along the drain grooves 20 and 22, when it strikes the junction 26 of the splice lines 34 and 38, will continue to flow downwardly through these drain grooves and will not flow backwardly or rearwardly along the splice line 38 because to do so would be to compel this drain water to flow uphill. By reference to a horizontal line it will be seen that the inclination of the two splice lines 26 and 38, when combined with the angle of inclination of the sections 2 and 4, would be in an upward or uphill direction. Hence, it will be seen that by reason of the peculiar arrangement of spliced lines which form the spliced joint of the two sections 2 and 4, I have provided a construction which will constantly and uniformly deflect the drain water or water of condensation into the drain grooves 20 and 22 and will prevent it from flowing to any other part of the roof bar and hence will prevent it escaping along the splice lines and dripping onto the purlins.

The present construction is adaptable to any type of roof construction or greenhouse construction wherein it is desired to drain the water, and it is likewise adaptable to various portions of a greenhouse roof construction irrespectively of whether or not the glass panels 24 are mounted directly upon the roof bar, as shown herein, or whether such glass panels 24 are mounted in the sashes of ventilating windows and which windows rest upon the flanged shoulders 30 of the roof bar, as for instance at that portion of the greenhouse construction which is adjacent the ridge pole.

Having thus described my invention what I claim as new and desire to secure by Letters Patent is:—

1. In a roof construction for a greenhouse, the combination of a purlin, two roof bar sections each having opposed drain guides along their sides and opposed shoulders at their upper portions for the reception of window panels, said sections having abutting spliced ends and lying at a downward inclination with respect to a horizontal plane, means holding said sections in assem- 125 130

bled relation and connected to a purlin, said sections having abutting lines of contact forming the spliced joint and which lines of contact are constructed and arranged so as to uniformly direct the drain water into the drain grooves of the roof bar.

2. Two roof bar sections adapted to form a spliced joint, each of said sections having a drain groove and a shouldered portion for the reception of glass panels disposed above said drain groove, said two sections having their abutting ends terminating in complementary splice faces adapted to be clamped together, said splice faces of each section comprising an intermediate face terminating at its upper end at the panel shoulder and at its lower end at the drain groove, and comprising an upper face terminating at one end at the upper face of the sections and 20 joining the shoulder end of the intermediate face, and comprising a third or lower face terminating at the drain gutter at its inner end and at the lower face of the sections at its lower end.

25 3. Two roof bar sections adapted to support window panels at their upper portions and provided with longitudinally disposed drain grooves on their sides, said ends terminating in complementary, angularly disposed splice faces the lowermost forward portion of said splice faces terminating in the drain grooves.

4. In a greenhouse construction, the combination of a purlin and a roof bar secured thereto and lying at an inclination to the horizontal, said roof bar having longitudinally extending drain grooves and being adapted to support window panels above said drain groove and said roof bar having 40 a spliced joint formed by intersecting faces, one of which inclines downwardly and forwardly and terminates in the drain grooves, said other faces being disposed at an upward inclination with respect to the horizontal plane.

5. In a roof construction for a greenhouse, the combination of a purlin and a roof bar mounted thereon and connected thereto and lying in a downward inclination with respect to a horizontal plane, said roof bar having longitudinally extending drain grooves, and being shouldered thereabove to receive the glass panels, said roof bar being composed of sections having spliced 50 abutting ends composed of angularly disposed faces, one of said faces being downwardly inclined with respect to a horizontal plane and terminating at the drain groove, and another of said faces connecting with the upper end of said first mentioned face and inclining downwardly and forwardly, and a third face connected with the bottom portion of said first mentioned face and inclining rearwardly and upwardly.

65 6. In a roof construction for a greenhouse,

the combination of a purlin having a flat face disposed at a downward inclination with respect to a horizontal plane, a channel-shaped metallic clamp bolted to the inclined face of said purlin, two roof bar sections having spliced ends composed of angularly disposed abutting faces nesting in said clamp, bolts passing through each of said sections and through said clamp to fasten said sections in assembled position, 70 each of said sections being formed with opposed longitudinally extending and registering drain gutters on each side of the sections and above said clamp and each of said sections having shouldered upper portions for 75 the reception of the transparent panels, said spliced faces abutting to form a drain line extending from the upper shouldered portion downwardly and forwardly to the gutters.

7. A spliced roof bar construction for a greenhouse roof, comprising two roof bar sections spliced together and lying at a downward inclination with respect to the horizontal, and provided with longitudinally 80 extending drain gutters, window panels carried by said sections, a portion of the splice for said sections being arranged to extend from the under surface of the panel in a downwardly forwardly inclined direction 85 which terminates in a drain gutter whereby to drain the water of condensation from the windows into said gutters.

In witness whereof, I have hereunto subscribed my name.
